DESIGN FOR A SHOE

Roger Vivier, New York, N. Y.

Application October 16, 1945, Serial No. 122,881

Term of patent 3½ years

(Cl. D7—7)

To all whom it may concern:

Be it known that I, Roger Vivier, a citizen of France, residing in New York city, county of New York, and State of New York, have invented a new, original, and ornamental Design for a Shoe, of which the following is a specification, reference being had to the accompanying drawing, forming part thereof.

Fig. 1 is a front perspective view of a shoe showing my new design.

Fig. 2 is a front perspective view of the opposite side shown in Fig. 1.

My design for a shoe of the step-in type is characterized by the specific placement of the bow on the outer side of the shoe, in connection with the contrasting colors of the various parts of the shoe as illustrated on the drawing.

I claim:

The ornamental design for a shoe, substantially as shown and described.

ROGER VIVIER.
